[57] CLAIM

The ornamental design for seat or similar article, as shown.

DESCRIPTION

FIG. 1 is a front perspective view of a seat showing my design in the form of an armchair.

FIG. 2 is a side view of the chair of FIG. 1.

FIG. 3 is a rear view of the chair of FIG. 1.

FIG. 4 is a sectional view, to an enlarged scale, taken along the section 4—4 in FIG. 2.

FIG. 5 is a sectional view, to an enlarged scale, taken along the section 5—5 in FIG. 2.

FIG. 6 is a front perspective view of the seat shown in the form of a sofa; and

FIG. 7 is a front elevational view thereof.
